UNITED STATES PATENT OFFICE

116,354

DESIGN FOR A PRAYER RAIL

Frank M. Wojtalewicz, Chicago, Ill.

Application June 5, 1939, Serial No. 85,349

Term of patent 3½ years

To all whom it may concern:

Be it known that I, Frank M. Wojtalewicz, a citizen of the United States, residing in the city of Chicago, in the county of Cook and State of Illinois, have invented a new, original, and ornamental Design for a Prayer Rail, of which the following is a specification, reference being had to the accompanying drawing, forming a part thereof.

In the drawing:

Fig. 1 is a front elevational view of a prayer rail showing my new design.

Fig. 2 is a side elevational view thereof; and
Fig. 3 is a top plan view.

I claim:

The ornamental design for a prayer rail, substantially as shown.

FRANK M. WOJTALEWICZ.
